REFRIGERATION

Glenn F. Zellhoefer, Bloomington, Ill.

Application December 5, 1935, Serial No. 53,027

3 Claims. (Cl. 62—118)

This invention relates to improvements in refrigeration and more particularly to an absorption type of refrigeration apparatus.

The absorption type of refrigeration apparatus includes a gaseous refrigerant and a liquid solvent adapted to form a solution with the gaseous refrigerant, and the apparatus therefore includes an absorber in which the solution is formed, a heater within which the gaseous refrigerant is boiled off or expelled, a rectifier through which the expelled gaseous refrigerant passes on its way to a condenser wherein the refrigerant is converted into a liquid, a cooling coil or evaporator into which the liquid refrigerant is discharged under reduced pressure to return to the gaseous state absorbing heat from the atmosphere surrounding the cooling element, and means for circulating the solution from the absorber to the heater and returning both the solvent after the refrigerant has been expelled in the heater and the refrigerant vapors from the evaporator to the absorber.

The rectifier is provided to free and return to the heater such of the vaporous solvent or solution in vapor form that may be carried over with the boiled-off or expelled refrigerant before entering the condenser. It is an object of this invention to provide an improved rectifier for the purpose above stated.

With this and other objects in view, reference is made to the accompanying sheets of drawings illustrating a form of this improved rectifier for an absorption refrigeration apparatus with the understanding that minor changes may be made without departing from the scope thereof.

In the drawings:

Figure 1 is a view in vertical transverse section taken through the end of an absorption refrigeration heater embodying the improved rectifier, as on the lines 1—1, Figure 2, showing the near manifold in elevation and with parts broken away.

Figure 2 is a view in central vertical longitudinal section taken on the line 2—2, Figure 1.

The heater and rectifier illustrated form a part of the system of an absorption refrigeration apparatus such as generally disclosed in this applicant's prior co-pending application Serial No. 736,232, filed July 20, 1934 which has matured into Patent No. 2,061,606, granted Nov. 24, 1936. It has been discovered when dichloromonofluoromethane, or a chemical of similar characteristics, is used as the refrigerant, and monoethyl ether of diethylene glycol acetate, or a chemical of similar characteristics, as the solvent, as disclosed in this applicant's prior co-pending ap-

plication Serial No. 756,977, filed December 11, 1934 which has matured into Patent No. 2,040,895, granted May 19, 1936, in an absorption refrigeration system, a problem arises in separating the solvent from the refrigerant before the gaseous refrigerant is discharged into the condenser different from the conventional commercial ammonia-water absorption apparatus.

The boiling point of the specified solvent is between 41° F. and 43° F. at atmospheric pressure, and the boiling point of the specified refrigerant is between 49° F. and 50° F. at atmospheric pressure. At 230° F. the vapor pressure of the solvent is approximately 20 mm., and at 180° F. the vapor pressure is approximately 1.5 mm. From this data it is seen that if the vapors of the solvent are cooled, after leaving the heater, to 180° F., it will theoretically condense out essentially all of the solvent vapors under the operating conditions of the apparatus, which is ordinarily between 25 and 30 lbs. of pressure in the heater.

This improved rectifier is so constructed as to provide sufficient eliminator surface through which the vapors pass and chill the vapors to between 140° F. and 180° F. after they leave the heater, and then provide an additional eliminator surface to insure that no particles of condensed solvent vapors carry over with the refrigerant vapors into the condenser.

The embodiment of this invention illustrated includes a cylindrical heater 1 mounting a plurality of steam pipes 2 arranged between manifolds 3 and 4 at the opposite ends of the heater with the manifold 3 connected to the source of steam, not shown, by pipe 5. It is preferable to mount the manifold 4 at a lower level than manifold 3 so that the condensate will drain from the pipes 2 thereinto and from which the condensate is removed by the pipe 6 leading from the bottom of said manifold. The manifolds 3 and 4 are positioned within the heater so that approximately one-third of the pipes 2 are above the longitudinal center-line and the pipes are preferably provided with a plurality of closely spaced radiating fins in the form of plates 7.

A bank of nozzles for spraying the solution or refrigerant mixture over the heater steam pipes 2 is provided in spaced-apart relation from the top of the heater 1 by mounting a plurality of nozzles 8 upon a series of parallel pipes 9 extending longitudinally of the heater from a manifold 10 at one end thereof connected by pipe 11 to the source of refrigerant mixture or solution supply, not shown.

The rectifier proper is formed of a cylindrical

casing 12 preferably arranged longitudinally above the top of the heater 1 of the same length but of considerably less diameter than the heater and in free communication with the interior of the heater, as by the plurality of large cylindrical conduits 13 spaced a short distance apart. A plurality of eliminators are provided preferably between the bank of nozzles and the top of the heater, and below and above a central longitudinal coil of pipe for circulating a cooling medium through the rectifier to reduce the temperature of the refrigerant vapors before the gaseous refrigerant passes through the discharge opening 14 of the rectifier to be conducted by a pipe, not shown, to the condenser. The cooling coil preferably includes a plurality of parallel rows of pipes 15 bent back upon thereabove, as shown, with their respective ends connected to manifolds 16 and 17 in communication with the supply and return lines of the circulating fluid, not shown. The pipes 15 are preferably provided with a plurality of closely spaced radiating fins in the form of plates 18. It is also preferable to provide a baffle plate 19 at the end of the heater to direct the spray from the end nozzle 8 upon the pipes 2 of the heater and a baffle plate 20 at the end of the rectifier 12 spaced apart from the discharge end to direct the refrigerant vapors over the cooling coil.

30 The eliminators are preferably composed of a plurality of small spherical bodies 21 of glazed refractory material held in close contact with each other between expanded metal plates 22. It is preferable to construct the eliminators in 35 the heater with the bottom expanded metal plate 22 supported upon the top of the parallel solution pipes 9 and with the top expanded metal plate 22 spaced apart from the top of the heater to form a chamber 23 thereabove which communicates with the rectifier 12 through conduits 13. It is also preferable to provide the eliminators above and below the cooling coil 15 in the rectifier 40 12 with the lower expanded metal plate 22 of the lower eliminator and the upper expanded metal plate 22 of the upper eliminator spaced apart from the adjacent rectifier walls to provide a chamber 24 at the bottom in communication with the chamber 23 above the heater eliminator and a chamber 25 above the upper eliminator in communication with the rectifier discharge 14.

50 If sufficient elimination of solvent from the refrigerant vapors is not effected, the solvent is carried over into the condenser and then into the evaporator, where a very small percentage of solvent will hold in solution a relatively large amount of refrigerant under the reduced pressure in the cooling coil or evaporator, the full vaporization of the liquid refrigerant will not occur, and consequently there is a loss of cooling effect.

60 It has been found in practice with the use of the refrigerant and solvent specified if the nozzles 8 for spraying the refrigerant mixture or solution are located approximately 2½ to 3 inches above the heating coils 2, the refrigerant vapors pass 65 through the spray and into the eliminator above the nozzle bank. In leaving this eliminator, the refrigerant will carry with it approximately 2½ per cent of solvent in the form of fine spray and vapor. The chamber 23 at the top of the heater affords ample space for equalization of flow of 70 said vapors through said first eliminator and through the conduits 13 into the chamber 24 to pass through the eliminator on the under side of the cooling coil. In leaving this second eliminator, the vapor will carry approximately 1 to 1½

per cent of solvent vapors which are precipitated out in passing over the cooling coil so that there remains at a temperature of 140° F. to 180° F. approximately ½ to ¼ of 1 per cent of solvent in the refrigerant vapors leaving the rectifier 12, which will not appreciably detract from operation of the evaporator.

The eliminator illustrated and described herein causes any refluxing that takes place to utilize the otherwise wasted heat of the hot vapors to re-vaporize a part of the gas that dissolves in the solvent that has been eliminated from the refrigerant vapors as it gravitates downward to the heating coil.

When solvents having sufficiently higher boiling points are employed, the rectifier cooling coils 15 may be omitted and the vapors collecting in the chamber 23 at the top of the heater 1 may be conducted by one or more conduits directly to the condenser. Such solvents may be dimethyl ether of tetraethylene glycol, diethyl ether of tetraethylene glycol, and methyl ethyl ether of tetraethylene glycol which have a vapor pressure of less than 3 mm. at 240° F. thereby insuring less than 1 per cent of solvent in 500 parts of refrigerant even though no cooling coil is used, but adequate illuminating surfaces must be employed. Those solvents are in other respects just as good or better than the ethyl ether of diethylene glycol but inherently more expensive under the present 30 methods of production.

When a cooling coil is used in the rectifier, the temperature of the coil is controlled in accordance with the characteristics of the solvent employed to insure the precipitation of the solvent vapor. This may be accomplished in any conventional manner as by providing a charged bulb element set in a well in the conduit of the vapors from the rectifier to the condenser to control a fluid valve in the cooling fluid line to the rectifier 40 cooling coil adjusted to produce the desired temperature therein.

Due to the relatively dense vapor of the specified refrigerant and the low surface tension of the specified solvents, there is a tendency for particles of the solvent to be carried along in the stream of outgoing refrigerant vapors in leaving the heater on the way to the condenser.

The characteristics of these chemicals are such that even with one lower boiling point solvent, such as ethyl ether of diethylene glycol, the amount of cooling required to insure a satisfactory separation of solvent and refrigerant is small provided any suspended particles of liquid solvent are separated from the gaseous refrigerant before the refrigerant is subjected to cooling. On the other hand, a failure to satisfactorily separate the suspended solvent liquid particles from the gaseous refrigerant before attempting to cool results in waste of a very large per cent of heat necessary to operate the equipment.

What I claim is:

1. In a heater or generator for an absorption refrigeration apparatus, employing a volatile, chemically stable, halogenated hydrocarbon, forming a dense vapor in the heater, as the refrigerant, and a solvent therefor having a low surface tension, the combination of means within the heater for freeing such vaporous solvent and solution from the vaporous refrigerant distilling from the solution and allow the freed solvent and solution to descend by gravity into the heater, said means including an eliminator spaced apart from the top of the heater comprising a plurality 75

of closely spaced spherical bodies of glazed refractory material.

2. In a heater or generator for an absorption refrigeration apparatus, employing a volatile, chemically stable, halogenated hydrocarbon as the refrigerant, and a solvent therefor, means for eliminating the vapors of the solvent and solution from the vaporous refrigerant in passing from the heater, including a rectifying chamber arranged above and in free communication with the top of the heater and a cooling coil arranged with said chamber, the temperature of which is sufficient to

precipitate out such vapors of solvent or solution that may be carried over with the refrigerant vapors, an eliminator spaced apart from the top of the heater comprising a plurality of closely spaced spherical bodies of glazed refractory material. 5

3. The structure of claim 2 wherein eliminators are spaced apart from the top and bottom of said chamber and arranged on both sides of said cooling coil. 10
